UNITED STATES PATENT OFFICE.

EDWARD H. BELDEN, OF PITTSBURGH, PENNSYLVANIA, ASSIGNOR TO BELDEN ENGINEERING COMPANY, OF PITTSBURGH, PENNSYLVANIA, A CORPORATION OF PENNSYLVANIA.

INTERNAL-COMBUSTION ENGINE.

1,045,500.

Specification of Letters Patent. Patented Nov. 26, 1912.

Application filed December 26, 1911. Serial No. 667,763.

To all whom it may concern:

Be it known that I, EDWARD H. BELDEN, a citizen of the United States, and a resident of Pittsburgh, county of Allegheny, 5 and State of Pennsylvania, have invented certain new and useful Improvements in Internal-Combustion Engines, of which the following is a specification.

My invention relates to internal combustion engines and has particular reference to improvements in the valves and valve gearing of internal combustion engines of the four-cycle type.

The objects of my invention are to simplify the construction and to lessen the cost 15 of such engines; to eliminate the vibration and the noise incident to their operation; to balance the valves thereof; and to increase the power, efficiency and durability 20 thereof.

My further purpose is to do away with the short-lived and noisy reciprocating valves and valve gearing now in common use and to substitute therefor a minimum 25 number of large substantial parts that cannot easily be broken; to balance the valves and otherwise arrange and construct them to offer the least possible resistance to the operation of the engine.

30 A special object of my invention is to provide an engine of the class named with a non-vibratory, constantly lubricated and substantially balanced admission and exhaust valve and to maintain it at a low temperature 35 protected from the hot gases of the cylinder.

Still other objects of the invention are to provide an internal combustion engine equipped with a balance valve and having 40 a cylinder which contains both the cylinder head and the necessary port-controlling means and from which both the head and the piston may be removed without disturbing the cylinder or said port controlling 45 means or gearing, and from which the valve may be removed without disturbing the cylinder or the valve gearing; and to provide an engine having valves and valve seats which shall be freely accessible upon removal of the cylinder head.

50 Another object of my invention is to provide a four-cycle engine conforming to the

foregoing outline and which may be made and assembled, dismembered and reassembled by ordinary mechanics and in less 55 time than other four-cycle engines.

A further object is to provide balanced rotary valves and valve gearing of such form and arrangement that the several cylinders of a multiple cylinder engine may 60 be economically formed in one block or casting.

Still further objects of my invention will appear hereinafter.

My invention resides in an internal combustion engine which, in its simplest form, has a single-piece ported cylinder, a single-piece cylinder head, a single-piece valve which is incased by the cylinder and the head and is substantially balanced therebetween, a single valve operating member and a single actuating and timing device which connects the valve operating member with the crank shaft. The simple structure here outlined is somewhat amplified in the higher 75 developments of my invention but even in its multiple cylinder forms I prefer to use only one valve operating member and one driving device.

The invention will be readily understood 80 upon reference to the accompanying drawings, which form part of this specification and in which I have depicted a preferred embodiment of my invention in a six cylinder internal combustion engine.

85 In the drawings: Figure 1 is a side elevation of my novel engine, four of the cylinders being shown in vertical longitudinal section; Fig. 2 is a horizontal section, substantially on the line 2^x—2^x of Fig. 1, all of the cylinder heads being removed; Fig. 3 is an enlarged horizontal section on the line 3^x—3^x of Fig. 4; Fig. 4 is a similarly enlarged vertical section on the line 4^x—4^x of Fig. 3; Fig. 5 is an enlarged vertical section on the line 5^x—5^x of Fig. 5; and Fig. 6 is an enlarged vertical section on the line 6^x—6^x of Fig. 1.

90 I have here illustrated my invention as embodied in a water-cooled multiple cylinder engine of a vertical type particularly adapted for use in automobiles. Its cylinders A, six in number, are arranged side by side in a single casting B. Various means

may be employed for cooling the cylinder and valve seats. For example the casting B may contain a water space or jacket C which is common to all the cylinders. The water space extends from the top B' of the casting to a point near the lower ends of the cylinders. The bottom B'' of the cylinder casting is secured upon the top of the base D. The base contains the crank shaft E shown in dotted lines in Fig. 1. On one end of the shaft E is a fly wheel F. The other end of the crank shaft carries a sprocket wheel G, (see dotted lines Fig. 1) the use of which will be explained hereinafter. Each cylinder A contains a piston H, joined to the crank shaft E by a connecting rod I, shown in dotted lines in Fig. 1. The cylinders open through both the top and the bottom of the casting B. They have separable heads J. The head J of each cylinder is preferably wholly contained within the upper or outer end of the cylinder. I make these ends of the cylinders large enough to receive the pistons so that the latter may be inserted and removed through the tops of the cylinders after the cylinder casting B has been fastened to the base D. The heads are larger than the pistons and each head rests upon an annular shoulder a^2 , which distinguishes the piston containing portion a^3 of the cylinder from its head containing portion a^4 . Both cylinder portions a^3 and a^4 are cylindrical. They are preferably concentric. The portion a^4 is large enough to contain not only the head but also the valve K, about to be described. Each head has an annular flange J' that fits the upper part of the cylindrical bore a^4 . The lower end J^2 of each head J snugly fits the piston bore a^3 of the cylinder and the annular shoulder J^3 of the head rests upon the cylinder shoulder a^2 as before explained. The upper end of the bore a^4 of each cylinder is threaded to receive a locking ring L, which is screwed firmly upon the flanged top of the head, completing an oil and pressure tight joint between the head and the cylinder at that point. If desired a key L' or a set screw may be added to lock the head against rotation. Such device, however, is not essential to the fastening of the head in the cylinder. The shoulder a^2 of the cylinder and the shoulder J^3 of the head are ground together and when the head is thus secured the shoulders form an oil and pressure tight joint between the lower end of the head and the cylinder. It will be observed that the concentricity of the cylinder and the head is insured by the close fitting of the upper end and the lower end of the head within the larger and the smaller bores a^4 and a^3 respectively of the cylinder. The intermediate portion of each head J, between the flange J' and the shoulder J^3 , is cylindrical and concentric with the containing bore a^4 . While this portion, as herein

shown, is larger than the piston bore a^3 , it is somewhat smaller than the bore a^4 and an annular cavity K' having parallel cylindrical walls is therefore formed between the cylinder and the head. The top of the cavity K' is formed by the underside of the head flange J'. The bottom of the annular cavity is formed by the cylinder shoulder a^2 on which the head rests. All of the walls of the cavity are finely ground and serve as seats for the valve K before referred to. The valves K are simple one-piece sleeves or rings that exactly fit their respective cavities K'. They are interchangeable. The inner and outer surfaces of each valve K are finely ground and are cylindrical and parallel. The top and bottom edges are also finely ground or finished and are parallel and perpendicular to the cylindrical surfaces.

85

In practice, the cross sectional dimensions of the valve K are approximately two thousandths of an inch smaller than the corresponding dimensions of the cavity K', leaving space for thin films of oil between all the opposed surfaces of the valve, cylinder and head. Obviously the space is increased at the oil groove K^x provided in the upper edge of the valve, and between the gear teeth on the valve. Each valve K contains at least one opening or port K², the same being of sufficient size to quickly admit and to quickly free the gases and being positioned about midway of the height of the valve. As shown in the drawings I prefer to provide each valve with two diametrically opposite ports K², so that one revolution of the valve shall serve for eight successive strokes, two complete power operations, of the piston, as hereinafter explained. Each cylinder is provided with an admission port and passage A^d and an exhaust port and passage E^x, these being formed in the casting B. The ports A^d and E^x open into respective valve cavities K' in position to register with the ports K² in the valve K. The width of the space between the inlet and exhaust ports approximately equals the width of the port K² in the valve K. These dimensions may be considerably varied without departing from the invention but I prefer to maintain the described proportions and relation for the particular reason that after the valve has opened to permit the heated gases to exhaust, those portions of the valve which are heated by the exhaust gases are almost immediately cooled by the inrush of cool combustible mixture at the port A^d. The time between the exhaust and the admission of mixture is proportionate to the distance that the valve has to travel between the ports E^x and A^d. In a multiple cylinder engine I prefer to pair the cylinders and connect the exhaust passages E^x of each pair as shown in Figs. 2 and 4. 130

130

From the points of juncture the exhaust passages extend downward and open through the lower part of the casting B.

5 E^x represents the vertical extension of the united exhaust ports of two cylinders.

E^{x2} represents the exhaust manifold of the engine.

As indicated in Fig. 2 I prefer that the admission passages A^d of the several cylinders shall be independent and shall open through the outer face of the casting above the exhaust manifold. The passages A^d are connected by an admission manifold A^{d2} having two connections A^{d3} and A^{d4} with a suitable carbureter A^{d5} . As best shown in Figs. 3 and 4 each head J contains a central cavity J^4 hemispherical at the top and opening through the bottom of the head. This cavity which obviously communicates 10 with the piston containing portion a^3 of the cylinder constitutes the compression and combustion chamber of the engine. A central hole is provided in the top of the head and in this hole is the device M for igniting 15 the gases, preferably an electric spark plug. Two passages $J-A^d$ and $J-E^x$ are formed in the head. These open through the valve seat surface of the head, at points directly and respectively opposite the ports A^d and 20 E^x in the valve seat surface of the cylinder, hence these passages or ports of the head are 25 in position to register with the ports K^2 in the valve K.

Referring now to Figs. 1, 2, 3 and 5, it 30 will be seen that the cylinder wall which forms part of the annular valve cavity contains a recess or cavity AB. This is positioned between the two ports A^d and E^x and preferably closer to the port A^d than to the 35 port E^x and may extend above and below said ports. Enough of the cylinder wall remains to afford proper lap for the valve around said ports A^d and E^x . The cavity AB opens against the outer periphery of the 40 valve K and its area is preferably less than the area of the port A^d . The recess or cavity AB is placed in communication with the piston space a^3 in the cylinder by means of a duct ab' , leading therefrom to a point 45 in the cylinder wall below the head J. When desired additional balancing cavities may be provided in the cylinder wall on the 50 opposite side of one or both of the ports A^d and E^x and I have shown an additional cavity ac upon the opposite side of the inlet port A^d . This cavity ac is arranged symmetrical with the cavity AB, that is, it is 55 placed equidistant from the inlet port A^d and its area is preferably substantially equal to the area of the cavity AB. It likewise 60 opens against the outer periphery of the valve and it may be placed in communication with the piston space A^3 of the cylinder by means of a short duct ac' similar to 65 the passage ab' and leading from the cavity to a point in the cylinder wall below the head J or it may be cross connected by short horizontal ducts a , b' , c' , shown in dotted lines in Fig. 1 either at one or both ends above and below the port A^d , with the cavity AB and thereby, in a practical sense, form a part of the balancing cavity AB. In other words, the two cavities AB and ac , when thus connected, form a single though divided 70 balancing cavity, the total area of which is preferably substantially equal to or slightly less than the area of the inlet port A^d . The head J contains a third passage, virtually a cavity: namely, the valve balancing passage or cavity JB which extends from the center cavity J^4 of the head through the valve seat surface of the head. This opening JB in the head is approximately opposite to the port JE^x . At times when the latter is closed by one side of the valve, the port JB is 75 also closed by the opposite side of the valve. The arrangement is such that one port K^2 of the valve registers with the head passage or cavity JB at times when the other port K^2 in the valve is passing the ports E^x and 80 JE^x in the cylinder and head. The area of the cavity JB in the head is preferably 85 slightly less than the area of the exhaust port E^x in the cylinder. The practical effect of this arrangement of the valve, the 90 ports and the cavities is that the revoluble valve is so nearly balanced in its cavity that it is but slightly seated across the cylinder ports A^d and E^x , even at the moment of maximum pressure within the cylinder. In 100 consequence, the valve is not permitted to cling upon any of its seats and it is not difficult to turn or rotate it in its cavity. At the same time, it will be noted that at 105 times of vacuum within the cylinder, as when the piston is descending and the admission port A^d and the valve port K^2 are in register the port JB together with the cavities AB and ac overbalance the exhaust port JE^x in the head with the result that 110 there is an unbalanced pressure serving to tightly hold the valve over the exhaust port E^x in the cylinder and prevent the indraft of gases from the exhaust passage E^x .

The valve operating mechanism is most clearly shown in Figs. 1, 2, 3 and 4. Each member K is a combined valve and gear wheel; that is, the lower outer edge of each valve K is provided with gear teeth K^3 constituting an integral wheel whereby the 115 valve may be rotated in its valve chamber or cavity. The valve operating member is arranged on the side of the engine opposite the side which contains the several admission and exhaust ports and the cavity AB. This 120 valve operating member comprises a single shaft N having as many integral gear wheel portions N as there are valves. Each cylinder is provided with an opening AN, at a point opposite the gear teeth on the 125

valve and considerably below the level of the ports K^2 in the valve. This opening admits the operating gear N' into mesh with the gear teeth upon the valve. Obviously 5 all of the openings AN are arranged in a horizontal line. The shaft N is held in suitable bearings N^2 provided on the side of the cylinder casting B , as shown in Figs. 2 and 3. The gear teeth on the valves and on the shaft N are preferably 45° spiral teeth. 10 Such gears operate readily in either direction and are noiseless. At its end, the shaft N is provided with a sprocket wheel N^3 and this is connected with the sprocket wheel G 15 on the crank shaft by a suitable sprocket chain G^a . The sprockets G and N^3 , and the sprocket belt G^a constitute the driver for the valve operating member or shaft N . The rotation of the crank shaft is thereby communicated 20 to the several valves, and the latter are rotated constantly during the operation of the crank shaft. The sprockets G and N^3 and the gears N' and K^2 are so proportioned that the valves are caused to turn 25 one-half of a revolution during each two revolutions of the crank shaft; *i. e.*, one complete revolution in the time consumed by eight piston strokes. It will be clear 30 that the rotative speed of the valves is relatively low and that nothing short of the breakage of one of these heavy substantial parts can interfere with the proper action of the valve. The valve operating shaft and gears are contained by a horizontal duct O 35 formed in the side of the cylinder casting. B^4 , B^4 are the edges of the duct O . These edges are integral with the cylinder casting B . The opening between them is closed by a vertical plate B^5 tightly bolted thereto 40 and making the duct oil tight. The duct O and the several valve cavities K' are in communication through the openings AN . The sprockets G and N^3 and sprocket belt G^a are inclosed by a casing P , the upper end 45 of which communicates with the duct O and the lower end of which communicates with the interior of the engine base D . An oil pump (not shown) forces oil into the duct O . The oil 50 is distributed therefrom to the several valves by the gear teeth on the valves K and shaft N ; *i. e.* by the gear wheels K^3 and N' . In the case of each valve, its rotation causes the oil to spread upon the outer surface of 55 the valve, whence it will work above and below the valve and spread upon the inner surface thereof. The oil groove K^x in the upper edge of the valve is best shown in Fig. 5. This groove provides an annular 60 oil pocket or reservoir for the accumulation of oil, to better distribute the oil upon the inner surface of the valve. As before explained, the differences of diameter, between the valve, the cylinder and the head, are so slight that only minute films of oil may 65

occupy the spaces. These are in fact capillary spaces and while the oil will freely work into and occupy the spaces, due to the rotation of the valve within the inclosing walls, the oil cannot easily be discharged from the 70 spaces by either internal or external pressure. The films of oil constitute fluid packings for the joints. This fact makes it possible to adequately lubricate the valves and inclosing walls without danger of gas leakage 75 from or to the cylinders at moments of compression, combustion and vacuum therein. It is clear also that it is practically impossible for any surface of the valve to engage any opposed surface upon the head or cylinder 80 except through the medium of this minute film of oil which envelops the valve. In consequence the valve and valve seats will operate indefinitely without perceptible wear. Very little of the oil thus supplied 85 to the valve is wiped off at the ports, the greater part returning to the trough through the openings AN . It will thus be seen that the valves, the valve cavities and the valve gears constitute an oil circulating 90 system which insures the positive lubrication of these parts at all times. The tight joint before alluded to, between the lower end of the head J and the cylinder prevents leakage 95 of valve oil into the cylinder. 99

As before explained, the water space C within the cylinder casting extends to the top of the cylinders and cooling water is therefore supplied to all of the upper parts of the cylinders except those portions or areas which are occupied by the admission and exhaust passages A^d , E^x and the gear openings AN . The cooling of the outer walls of the valve cavities and the outer portions of the valves is thus insured. Each head J contains a water space J^w . The water is supplied and discharged through pipes J^p , two of which are provided for each head. The top of the head contains a depression to admit, and to afford easy access to, the firing plug M . The space J^w occupies nearly the whole of the head, only thin walls remaining; the exceptions being the space occupied by the ports JA^d and JE^x . As before described, the head is deeper than the valve K , 100 extending both above and below the same. The water space is likewise deep, its bottom being preferably below the level of the valve K and the water rising therein to a level 105 above the top edge of the valve. In other words, the cooling surface of the valve wall of the head is practically co-extensive with the valve and the maintenance of the valve at a low temperature is positively insured. It is not material whether these walls which 110 inclose or envelop the valve are cooled by water or by air, or by some other medium; the important point is that the valves and the inclosing walls are so formed and related that they are quite separate from the 115 120 125 130

hotter portions of the cylinder and head and are fully exposed to the cooling medium.

The operation of the engine is according to the well known four-cycle principle and will be clearly understood from the foregoing detailed description of the operation of its several related parts.

As various modifications of my invention will readily suggest themselves to one who is skilled in the art, I do not confine or limit the invention to the specific constructions herein shown and described.

The valve construction herein shown is described and claimed in U. S. Patent No. 1,017,073, issued to me February 13, 1912, and is not claimed herein.

An engine provided with a balancing port resembling the port JB hereof is described and claimed in U. S. Patent No. 1,017,074 issued to me February 13, 1912.

An engine provided with a balancing cavity resembling the cavity AB hereof is described and claimed in U. S. Patent No. 1,017,075 issued to me February 13, 1912.

The combination of parts, including the shaft N for actuating the valve, comprises the subject matter of my co-pending application No. 667,764. The scope of this present application is set forth in the patented claims.

The several constructions above referred to having been respectively broadly claimed in the co-pending applications, are not claimed herein.

Having thus described my invention, I claim as new and desire to secure by Letter Patent:

1. In an internal combustion engine, a cylinder and a piston therein, in combination with a cylinder head fixed in the end of said cylinder, the inner and outer ends of said head being tightly jointed to said cylinder, the intermediate portion of said head being of less diameter than the adjacent portion of the cylinder and concentric therewith, an annular valve cavity being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing a port positioned to register with aforesaid ports, said cylinder containing a balancing cavity opening into said valve cavity between the ports in the cylinder and in communication with the piston space in the cylinder and said head containing a balancing port approximately diametrically opposite the exhaust port, and means for rotating said valve in said valve cavity in time with the movements of said piston.

2. In an internal combustion engine, a cylinder and a piston therein, in combination

with a cylinder head fixed in the end of said cylinder, the inner and outer ends of said head being tightly jointed to said cylinder, the intermediate portion of said head being of less diameter than the adjacent portion of the cylinder and concentric therewith, an annular valve cavity being thereby formed between said ends of the head, one side of said head and cylinder containing an admission and an exhaust port which open into said cavity, an annular valve of slightly greater diameter than the head and of slightly less diameter than said adjacent portion of the cylinder and occupying said cavity, said valve containing two diametrically opposite ports positioned to register with aforesaid ports, the distance between the ports in the cylinder approximately equaling the width of each port in the valve, said cylinder containing a balancing cavity opening into said valve cavity between its ports, said head containing a balancing port approximately diametrically opposite to the exhaust port in position to register with the ports of the valve and means for rotating the valve once during every eight strokes of the valve.

3. In an internal combustion engine, a cylinder and a piston therein, in combination with a cylinder head, the cylinder having admission and exhaust ports in one side, an annular valve positioned within the cylinder, concentric therewith and adapted to close said ports, said valve having an opening adapted to register with aforesaid ports, said cylinder containing a balancing cavity in one side adjacent to its ports and of substantially equal area with each thereof opening against said valve and communicating with the piston space in the cylinder, said head also containing a balancing port diametrically opposed to the exhaust port and of substantially the same area, in position to register with the port in the valve, means for supplying oil to said valve, and means for operating said valve in time with the movements of said piston.

4. In an internal combustion engine, a suitably cooled cylinder and a piston therein, in combination with a suitably cooled cylinder head fixed in the end of said cylinder, said head being of less diameter than the adjacent portion of the cylinder and concentric therewith, an annular valve cavity being formed thereby, said head and cylinder containing admission and exhaust ports which open into said cavity, an annular valve occupying said cavity and cooled by the cylinder and head, said valve containing a port positioned to register with aforesaid ports, said cylinder containing a balancing cavity opening through the outer wall of said valve cavity adjacent to the inlet port in the cylinder in communication with the piston space in the cylinder and in position

to register with the port in the valve, the head containing a balancing port approximately diametrically opposite to the exhaust port and positioned to register with the port in the valve and valve operating gearing deriving motion from said piston.

5. In an internal combustion engine, a cylinder and a piston therein, in combination with a cylinder head fixed in the end of said cylinder, said head being of less diameter than the adjacent portion of the cylinder and concentric therewith, an annular valve cavity being thereby formed between the cylinder and head, one side of said cylinder containing admission and exhaust ports which open into said cavity, a port controlling sleeve valve occupying said cavity, said cylinder containing a balancing port which opens against the valve on each side of the inlet port in the cylinder, and gearing through which the piston operates the valve to open and close said ports in time with the piston movements.

6. In an internal combustion engine, a cylinder in combination with a piston therein, a head within the end of the cylinder, means securing said head against movement in said cylinder, said cylinder and head having corresponding admission and exhaust ports, an annular valve disposed concentrically with and between the head and cylinder, said cylinder containing a balancing cavity which opens against the outer periphery of said valve adjacent to each side of the inlet port in the cylinder, said head containing a balancing port which opens against inner periphery of the valve and positioned approximately diametrically opposite to the exhaust port in the cylinder and valve operating gearing acting on the valve and deriving motion from said piston.

7. In an internal combustion engine a cylinder having a piston containing portion and a head containing portion, in combination with a head having its inner end in circumferential and endwise engagement with the walls of said piston containing portion and having its outer end circumferentially engaged with the walls of said head containing portion of the cylinder, means securing the head against movement in the cylinder and effecting tight joints between said ends of the head and the cylinder, ports in said cylinder and the intermediate portion of the head, an annular valve cavity being provided between the head and cylinder and between said joints, an annular ported valve fitting said valve cavity and rotatable therein to control said ports, said cylinder containing a balancing cavity between said ports and positioned closer to the inlet port than to the exhaust port and opening against the outer periphery of the valve, said head containing a balancing port approximately diametrically opposite

to the exhaust port in the cylinder and positioned to register with the valve port and means for rotating the valve in time with the piston movements.

8. In an internal combustion engine, a cylinder having a cylindrical piston containing portion and a head containing portion, in combination with a head having an intermediate valve seating portion of less diameter than the head containing portion of said cylinder, said head having its inner end and its outer end engaged with the walls of said piston containing portion and said head containing portion respectively, means fastening said head against movement in the cylinder and effecting tight joints between the cylinder walls and said ends of the head, an annular valve cavity which is closed at its ends being formed by and between said cylinder and said head and situated wholly between the outer end of the cylinder and the inner end of the head, admission and exhaust ports provided in the cylinder and the head and opening into said cavity, a balancing cavity in the cylinder and opening into said valve cavity, an annular valve occupying substantially the whole of said valve cavity and provided with a port to register with said admission and exhaust ports and said cavity, a balancing cavity in said head approximately diametrically opposite to the exhaust port in the cylinder and positioned to register with the port in the valve, and means engaging the periphery of said valve and adapted to rotatively move said valve in said cavity.

9. In an internal combustion engine, a cylinder in combination with a head the ends of which make oil tight joints with the cylinder, an annular valve space or cavity being provided between the cylinder and the head and between said joints, a valve revolvably movable in said cavity, said valve having a port and said cylinder and said head being both provided with admission and exhaust ports which communicate with said cavity, said cylinder containing a balancing cavity between its ports and said head having a balancing cavity approximately diametrically opposite to the exhaust port in the cylinder positioned to register with the valve port, said balancing cavity and balancing port serving to ease the valve across the inlet and exhaust ports during moments of pressure in the cylinder and to press the valve against the ported portion of the cylinder during moments of partial vacuum within the cylinder, and means for operating said valve.

10. In an internal combustion engine, a cylinder having a piston containing portion or bore and a valve and head containing portion or bore distinguished by a valve and head seating shoulder, in combination with an annular sleeve valve containing a

port, fitting said valve and head bore of the cylinder and seated on said shoulder of the cylinder, a head fitting within the valve and having its inner end seated upon said shoulder at the end of said valve, means securing the head against movement in the cylinder and effecting tight joints between the head and cylinder at the ends of the head, said cylinder having a balancing port which 13 opens against the outer periphery of said valve, said head having a balancing port approximately diametrically opposite to the exhaust port in the cylinder and opening against the inner periphery of the valve, 15 and a suitable valve actuator and a driver therefor.

11. In a four-cycle internal combustion engine, a single cylinder block or casting containing a plurality of cylinder bores in 20 combination with cylinder heads, one within each said bore, an annular sleeve valve between each head and cylinder bore and enveloped thereby, said heads, valves and cylinders having suitable registering inlet and 25 exhaust ports, each said cylinder having a balancing port which opens against the outer periphery of the valve, each head having a balancing port approximately diametrically opposite to the exhaust port of its 30 cylinder, a valve actuating member for simultaneously rotating said valves thereby causing the periodic registry of said ports, and means for driving said member.

12. In a four cycle internal combustion engine, a single cylinder block or casting containing a plurality of cylinder bores in combination with cylinder heads, one within each said bore, an annular sleeve valve between each head and cylinder bore, said 40 heads and cylinders being tightly jointed above and below respective valves, said heads, valves and cylinders having suitable registering ports, each said cylinder having two balancing cavities opening against the 45 outer periphery of its valve and each said head having a single balancing cavity opening against the inner periphery of its valve, a single valve actuating member for simultaneously rotating said valves thereby causing the periodic registry of said ports and 50 a single duct containing said member and supplying oil to all said valves.

13. In an internal combustion engine, a one piece cylinder containing a cylinder bore comprising a piston containing portion and 55 a head containing portion, in combination with a one-piece ported sleeve valve concentric with and fitting the head containing portion of said bore, a one piece head concentric with and fitting said valve, the ends 60 of said head being jointed to the cylinder above and below respective ends of said valve, said cylinder and head containing admission and exhaust ports to register with 65 the port in the valve, means for rotating said

valve, said head containing a balancing port opening against the inner periphery of the valve approximately diametrically opposite to the exhaust port and the cylinder containing balancing cavities opening 70 against the outer periphery of the valve adjacent to the admission port.

14. In an internal combustion engine, a one-piece cylinder containing a cylinder bore comprising a piston containing portion and a head containing portion, in combination with a one-piece plurally ported sleeve valve concentric with and fitting the head containing portion of said bore, a one-piece head concentric with and fitting said valve, 80 the ends of said head being jointed to the cylinder above and below respective ends of said valve, said cylinder and head containing admission and exhaust ports to register with successive ports in the valve, said head containing a balancing port opening against the inner periphery of said valve approximately diametrically opposite the exhaust port in the cylinder and said cylinder containing balancing cavities opening against 85 the outer periphery of the valve adjacent to the admission port of the cylinder and in communication with the piston space of the cylinder, and means for rotating said valve.

15. In an internal combustion engine, a cylinder and a piston therein, in combination with a head concentric with and fixed in the end of said cylinder, said head having inner and outer ends which make tight joints with the cylinder, the cylinder and head 100 having corresponding admission and exhaust ports in one side thereof between said joints, an annular valve of slightly greater diameter than said head and of slightly less diameter than the cylinder longitudinally fixed 105 therein between said joints and having a port adapted to register with the aforesaid ports, the distance between the ports in the cylinder approximating the width of said port in said valve, a balancing port in said 110 head approximately diametrically opposite the exhaust ports, balancing cavities in the cylinder opening symmetrically on each side of the inlet ports, the combined areas of the balancing cavities and the balancing port 115 being slightly less than the combined areas of said first mentioned ports, means for supplying oil to said valve, and means for operating said valve in time with the movements of said piston.

16. In an internal combustion engine, a cylinder and a piston therein, in combination with a cylinder head fixed in the end of said cylinder, the inner and outer ends of said head being tightly jointed to said cylinder, the intermediate portion of said head being of less diameter than the adjacent portion of the cylinder and concentric therewith an annular valve cavity being thereby formed between said ends of the head, one 125 130

side of said head and cylinder containing admission and exhaust ports which open into said cavity, an annular valve of slightly greater diameter than the head and of slightly less diameter than said adjacent portion of the cylinder and occupying said cavity, said valve containing two approximately opposite ports positioned to register with aforesaid ports, balancing cavities in said head and cylinder respectively opposite the exhaust and admission ports and positioned to register with the ports in the valve, an opening in that side of the cylinder which is adjacent to the balancing cavity in the head, valve operating means positioned in said opening, means for supplying oil to said operating means and valves, and a driving connection between said piston and said valve operating means.

17. In an internal combustion engine, a cylinder and a piston therein, in combination with a head concentric with and fixed in the end of said cylinder, said head having inner and outer ends which make tight joints with the cylinder, the cylinder and head having corresponding admission and exhaust ports in one side thereof between said joints, an annular valve of slightly greater diameter than said head and of slightly less diameter than the cylinder longitudinally fixed therein between said joints and having one or more ports adapted to register with the aforesaid ports, the distance between the ports in the cylinder approximating the width of said port in said valve, balancing cavities in said cylinder adjacent to the ports therein, and the side of the head opposite to the inlet and exhaust ports containing an additional balancing cavity, the total area of said balancing cavities approximating the combined area of said admission and exhaust ports, and means for rotating said valve in time with the movements of said piston.

18. In an internal combustion engine, a cylinder and a piston therein, in combination with a cylinder head fixed in the end of said cylinder, the inner and outer ends of said head being tightly jointed to said cylinder, the intermediate portion of said head being of less diameter than the adjacent portion of the cylinder and concentric therewith an annular valve cavity being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing a port positioned to register with aforesaid ports, said cylinder containing a balancing cavity opening into said valve cavity adjacent the ports in the cylinder and in communication with

the piston space in the cylinder, said head containing a balancing port co-operatively arranged to assist said balancing cavity and valve operating gearing deriving motion from said piston.

19. In an internal combustion engine, a cylinder and a piston therein, in combination with a cylinder head fixed in the end of said cylinder, the inner and outer ends of said head being tightly jointed to said cylinder, the intermediate portion of said head being of less diameter than the adjacent portion of the cylinder and concentric therewith an annular valve cavity being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing a port positioned to register with aforesaid ports, said cylinder containing a balancing cavity opening into said valve cavity adjacent the ports in the cylinder and in communication with the piston space in the cylinder, said head containing a balancing port positioned to operatively co-operate with said balancing cavity to relieve said valve of unbalancing pressure, and valve operating gearing acting on the valve adjacent the balancing port in the head and deriving motion from said piston.

20. In an internal combustion engine, a cylinder and a piston therein, in combination with a cylinder head, both the head and cylinder having admission and exhaust ports in one side, an annular valve positioned within the cylinder between the head and concentric therewith and adapted to close said ports, said valve having one or more ports adapted to register with aforesaid ports, said cylinder containing a balancing cavity opening against the outer side of said valve and communicating with the piston space in the cylinder, said head containing a balancing cavity opening against the inner side of said valve, means for supplying oil to said valve, and means for operating said valve in time with the movements of said piston.

21. In an internal combustion engine, a cylinder and a piston therein, in combination with a cylinder head fixed in the end of said cylinder, said head being of less diameter than the adjacent portion of the cylinder and concentric therewith an annular valve cavity being thereby formed between the head and cylinder, said head and cylinder containing admission and exhaust ports which open into said cavity, an annular valve occupying said cavity, said valve containing a port positioned to register with aforesaid ports, said cylinder containing a

balancing cavity opening into said valve cavity adjacent the ports in the cylinder and in communication with the piston space in the cylinder, said head containing a balancing port positioned to add to the balancing effect produced upon the valve by said balancing cavity and valve operating gearing deriving motion from said piston.

22. In an internal combustion engine a cylinder containing admission and exhaust ports positioned in the walls near the head of the cylinder, in combination with a piston in said cylinder, a sleeve valve concentric with the portion of the cylinder containing said ports, a cylinder head closing the end of the cylinder, fitting within said valve and having complementary admission and exhaust ports, means for actuating said valve to open and close said ports, and cavities in both the cylinder and head opening against the valve, said cavities balancing the effect of said ports on said valve.

23. In an internal combustion engine, a cylinder and a piston therein, in combina-

tion with a cylinder head fixed wholly within the end of said cylinder, said head being of less diameter than the adjacent portion of the cylinder and concentric therewith an annular valve cavity being thereby formed between the cylinder and head, one side of said cylinder containing admission and exhaust ports which open into said cavity, a port controlling sleeve valve occupying said valve cavity and balancing cavities in the cylinder and head allowing pressure to operate upon the inner and outer peripheries, respectively, of said valve and substantially balancing said valve in said cavity, and valve operating gearing acting on the valve and deriving motion from said piston.

In testimony whereof, I have hereunto set my hand, this 20th day of Dec., 1911, in the presence of two subscribing witnesses.

EDWARD H. BELDEN.
